DESIGN FOR A VENDING MACHINE CABINET

Peter Schladermundt, Bronxville, N. Y., and Charles L. Metzler, Palisades Park, N. J., assignors to C. Earl Hovey, trustee, Kansas City, Mo.

Application February 21, 1944, Serial No. 112,660

Term of patent 14 years

(Cl. D52—3)

To all whom it may concern:

Be it known that we, Peter Schladermundt and Charles L. Metzler, citizens of the United States, residing at 8 Park Avenue, Bronxville in the county of Westchester and State of New York, and 511 Orchard Avenue, Palisades Park, in the county of Bergen and State of New Jersey respectively, have invented a new, original, and ornamental Design for a Vending Machine Cabinet, of which the following is a specification, reference being had to the accompanying drawings, forming a part thereof.

Fig. 1 is a perspective view of the vending machine cabinet, showing our new design.

Fig. 2 is a front elevational view thereof; and Fig. 3 is a side elevational view thereof.

We claim:

The ornamental design for a vending machine cabinet, as shown.

PETER SCHLADERMUNDT.
CHARLES L. METZLER.
